UNITED STATES PATENT OFFICE.

PORFIRIO P. PÉREZ AND FERNANDO SANTANA BATISTA, OF KEY WEST, FLORIDA.

WRENCH.

1,245,017.

Specification of Letters Patent.

Patented Oct. 30, 1917.

Application filed February 7, 1917. Serial No. 147,087.

To all whom it may concern:

Be it known that we, PORFIRIO P. PÉREZ and FERNANDO SANTANA BATISTA, citizens of and residents of Key West, in the county 5 of Monroe and State of Florida, have invented a new and Improved Wrench, of which the following is a full, clear, and exact description.

The invention relates to a wrench adapted for general purposes and particularly effective as a pipe wrench.

Objects of the invention are to provide an improved adjustable retaining means for the movable jaw of the wrench and to improve the manner of forming and yieldingly mounting the relatively fixed jaw.

The nature of the invention and its advantages will clearly appear as the description proceeds.

20 Reference is to be had to the accompanying drawings forming a part of this specification in which similar reference characters indicate corresponding parts in all the views.

25 Figure 1 is a side elevation of a wrench constructed in accordance with our invention;

Fig. 2 is a front view thereof;

Fig. 3 is a cross section on the line 3—3,

30 Fig. 1;

Fig. 4 is a cross section on the line 4—4, Fig. 1.

The wrench includes a suitable handled shank 10 at the front end of which is mounted a jaw 11 by a pivot pin 12. The said pin passes through a lug 13 on the jaw 11, said lug being received in a recess 14 in the front end of the shank 10.

Forward of the pivot 12 the shank 10 is 40 formed with a rigid lateral arm 15 and the jaw 11 is recessed at the front to produce side flanges 16 that overlap the sides of the arm 15, thereby bracing and giving guided movement to the jaw 11. The jaw 11 is 45 subject to a compression spring 17 which abuts against the back of the said jaw adjacent to the bases of the flanges 16, and abuts at its opposite end against the opposed surface of the arm 15. Thus the spring is 50 housed between the flanges 16 and permits the jaw to yield in gripping a pipe. At the outer end of the recess 14, a curved surface 18 is produced on the shank 10, the curve being struck with the pivot 12 as a center, 55 and the opposed surfaces 19 of the flanges 16

are correspondingly curved. By the described arrangement it will be seen that the spring 17 and the fixed abutment 15 are disposed at the same side of the wrench as the jaws and housed by the jaws 11, so that no 60 additional projecting elements are disposed at the back of the wrench, the lateral projection represented by the jaw 11, representing the total lateral projection at the wrench head.

The movable jaw 20 is slidable on the shank 10 to or from the jaw 11. At the inner face of the jaw 20 is a longitudinal series of teeth 21 which are adapted to interlock with mating teeth 22 on the opposed 70 side of the shank 10. The opposite face or back of the shank 10 is formed with a longitudinal series of teeth 23 with which teeth 24 on a block 25 are adapted to interlock, whereby to grip the shank between the jaw 75 20 and the said block 25.

Links 26 are pivoted as at 27 to the side faces of the jaw 20 and the block 25, and links 28, parallel with the links 26, are pivoted as at 29 to the side faces of the said 80 movable jaw and block, the arrangement being such that a movement of the links will cause the jaw 20 and the block 25 to be released from the toothed shank 10. The links 28 have pins 30 projecting from the 85 inner faces thereof into longitudinal grooves 31 formed in opposite sides of the shank 10 so that in addition to the pivotal connection of the links with the movable jaw and the locking block 25, the links 28 may be 90 rocked on the pins 30 as fulcrums.

The links 28 are formed integral with a head 32 and a compression spring 33 is provided and disposed longitudinally of the wrench between the said head 32 and the 95 rear surface of the jaw 20, one end of the spring being received on a pin 34 on the head 32 and the opposite end on a pin 35 on the jaw. The tendency of the spring is to rock the links 30 to a position to cause a 100 locked engagement of the jaw 20 and block 25 with the toothed shank 10. To slide the movable jaw 20, pressure is exerted by the palm of the hand against the curved back surface 36 of the head 32, the fingers of the 105 hand at the same time gripping a lateral projection 37 on the jaw 20 for compressing the spring 33. The slideable jaw may then be slid on the shank to the desired position and upon release of the pressure of the hand 110

on the head 32 and member 37, the spring 33 will cause the jaw 20 to be locked in the adjusted position. The jaw 11 is curved toward the outer end for effective action in gripping a pipe while the inner portion of the gripping surface of the jaw is more nearly perpendicular of the shank for engagement with a nut.

Having thus described our invention we 10 claim as new and desire to secure by Letters Patent:

1. A wrench including a handled shank, a movable jaw thereon, and a relatively fixed jaw, the front and back surfaces of the said 15 shank being toothed, said movable jaw having teeth to engage the opposed teeth on the shank, a gripping block at the back of the shank and toothed to engage the opposed teeth on the shank, parallel front and rear 20 links extending at the sides of the shank and pivotally connected with the movable jaw and the gripping block, the rear links being integral with a head positioned at the rear of the movable jaw, and a spring interposed between the said head and the movable jaw and disposed longitudinally of the wrench.

2. A wrench including a handled shank having teeth on the front and back surfaces thereof, a fixed jaw on the shank at 30 the front end, a movable jaw rearward of

the fixed jaw and having teeth to engage the opposed teeth on the shank, a gripping block at the back of the shank, link connections between the movable jaw and the gripping block, near the forward and rear ends of said block, the rear links being integral with a laterally extending head having a curved rear surface adapted to be pressed against by the palm of the hand, the movable jaw presenting a rearwardly disposed surface opposite the said head and having a finger-hold at the outer end of said surface, and a spring interposed between the said head and the said movable jaw adjacent to 40 the said finger-hold.

3. A wrench including a handled shank, a slideable jaw thereon, and a second jaw on the shank in front of the movable jaw, the second jaw having a lug and the shank having a recess receiving said lug, a pivot extending through the shank and through the said lug, a rigid lateral arm on the shank in front of the pivot, forwardly extending flanges on the pivoted jaw at the front, said 50 flanges extending at the sides of the fixed lateral arm of the shank, and a spring housed between the said flanges and abutting at its ends against the pivoted jaw and the said fixed arm.

PORFIRIO P. PÉREZ.

FERNANDO SANTANA BATISTA.
